(57) **CLAIM**

The ornamental design for a tailgate pad, as shown.

DESCRIPTION

FIG. 1 is a front elevational view of a tailgate pad, according to our new design;

FIG. 2 is a top perspective view thereof;

FIG. 3 is a rear perspective view thereof;

FIG. 4 is a top, left side elevation view thereof;

FIG. 5 is a rear, right side elevation view thereof;

FIG. 6 is a right side elevation view thereof; and,

FIG. 7 is a left side elevation view thereof.

The shade lines in the Figures show contour and not surface ornamentation.

The broken lines in the drawings illustrate portions of the tailgate pad that form no part of the claimed design.

1 Claim, 7 Drawing Sheets
